HOIST

Ferdinand G. Welke, San Francisco, Calif., assignor to Shell Development Company, San Francisco, Calif., a corporation of Delaware

Application March 20, 1936, Serial No. 69,790

1 Claim. (Cl. 254—100)

This invention is concerned with a jack for raising the weight of the body of an automobile or other vehicle from its axles.

It is a present practice in order to thoroughly lubricate the springs and associated members of an automobile truck or like vehicle, to remove the weight of the body from the springs. By this procedure, as will be apparent, it is possible for the grease or oil to penetrate into the spring shackles and between the leaves of the leaf springs with which such vehicles are generally provided. A usual practice is to raise the body of the automobile by means of a jack, the base of which rests upon the ground or upon a cross member of an automobile elevator or hoist upon which the vehicle may be driven in order that the chassis may be made more accessible. These jacks present a disadvantage in that a slight movement of the vehicle upon the hoist or other base upon which the vehicle is resting will cause the body to be dislodged from the end of the jack with possible injury to the man working under the vehicle. Another disadvantage of such jacks is that they are, of necessity, relatively heavy. It is therefore, an object of this invention to devise a jack for raising the body and frame of a vehicle from its axles which will avoid the above disadvantages.

It is another object of this invention to provide a jack which will raise the body of the vehicle from its chassis without taking any weight off the wheels of the vehicle.

The further objects of my invention will be apparent to those skilled in the art from the following detailed description of a specific embodiment of my invention throughout which reference is made to the accompanying drawing of which: Figure 1 is a partial sectional elevation of the hoist. Figure 2 is a view showing the hoist in use upon an automobile, only part of which is shown. Figure 3 is an end view of the hoist with chain removed.

Referring to Figures 1 and 3, the body of the hoist comprises a square tube 1 having securely mounted on one exterior face and towards one end a hooked arm 2. Slidably mounted in the bore of the square tube 1 is a square threaded nut 3 having attached to its upper side one end of a round tube 4 which tube is also slidably mounted in the bore of said square tube 1. The free end 5 of the tube 4 is knurled and hardened, the object of which will appear later herein. A jack screw 6 is threaded into the nut 3. The end of the jack screw towards the hook 2 is provided with a shoulder 7. Upon the side of the shoulder opposite the screw-threaded portion of the jack

screw, a rod 8 extends which terminates in a T-handle 9, having a crank 10 at one end. The shoulder 7 abuts against a thrust washer 11, held in place by a thrust sleeve 12.

A flexible metallic member such as a chain 13 provided with a square shaped link 14 at one end forms part of the jack. The square shaped link 14 is of such size that it can slide upon the square tube 1. The hook arm 2 is provided with a slot 15 so that adjustment of the length of chain between the square link 14 and the hook 2 can be readily made.

The hoist is used as follows: Referring to Figure 2, the chain 13 is first placed around the axle 16 and the free end pulled tight and a link passed into the slot 15 of the hook 2. The handle 9 of the hoist is then turned and the upper knurled end 5 of tube 4 directed to contact a rivet or other suitable surface on the frame 17 or associated part of the vehicle. Continued turning of the handle will remove the weight of the frame and body from the springs 18 and the shackles 19, transferring the same directly to the axle 16 so that lubricant can more readily be placed between the leaves of the spring and reach the normal lead carrying surfaces of the shackles. As will be apparent to those skilled in the art the hoist readily adapts itself to use on all types of vehicles, which has not been the case with previous hoists operating between an axle and the frame and body. Furthermore, a particular advantage of my device is that it is safer than existing jacks. The chain 13 securely holds the jack to the axle and the pressure on the knurled head prevents the upper end of the device sliding off the frame. An incidental advantage is that the hoist is far less expensive than known devices.

Whereas in this specification I have described a preferred form of my device it should be understood that I may make modifications thereof within the scope of the claim appended hereto.

I claim as my invention:

An automobile hoist comprising a jack screw, a tubular member mounted thereon said tubular member having a serrated contact surface at its upper end, a casing of rectangular cross section for said jack screw, a chain for attaching said casing to an axle of an automobile, one end link of said chain being adapted to pass over the upper end of said tubular member and to slide on said rectangular shaped casing, jaws mounted on the lower end of said casing adapted to receive the other end of said chain, and a crank arm mounted on the lower end of said jack screw substantially as described.

FERDINAND G. WELKE.
